UNITED STATES PATENT OFFICE.

MATTHEW F. BAYER, OF KENOSHA, WISCONSIN, ASSIGNOR TO SIMMONS COMPANY, OF KENOSHA, WISCONSIN, A CORPORATION OF DELAWARE.

CRIB-LOCK.

1,371,597.

Specification of Letters Patent. Patented Mar. 15, 1921.

Application filed September 15, 1919. Serial No. 323,689.

To all whom it may concern:

Be it known that I, MATTHEW F. BAYER, a citizen of the United States, residing at Kenosha, in the county of Kenosha and State of Wisconsin, have invented certain new and useful Improvements in Crib-Locks, of which the following is a specification.

My invention relates to improvements in crib lock and has particular reference to a type of crib embodying a main frame and a side frame or gate which is capable of being lowered to facilitate removal, or work upon the crib contents.

The principal objects of the invention are to provide a construction which may be operated by one hand only, either when being disengaged or when being locked in position; to provide a construction which shall be simple in design and economical to manufacture, and in general, to provide an improved construction of the character referred to.

In the drawings which illustrate my invention as applied to a child's crib in which the side is capable of being raised or depressed,

Figure 1 is a side elevation of the crib;

Fig. 2 is an enlarged side elevation of the locking means and associated parts;

Fig. 3 is a section taken on the line 3—3 of Fig. 2;

Fig. 4 is a section taken on the line 4—4 of Fig. 2;

Fig. 5 is a perspective view of the slotted bracket with which the lock pin co-operates;

Fig. 6 is a side elevation of the rod foot;

Fig. 7 is a section taken on the line 7—7 of Fig. 6;

Fig. 8 is a section taken on the line 8—8 of Fig. 6; and

Fig. 9 is a section taken on the line 9—9 of Fig. 6.

Referring to the drawings, it will be observed that the two-corner posts 10 at the front of the crib, constitute the supports for the movable frame part, or side gate 11, said gate comprising tubular top and bottom rods 12 and 13 and vertical filler tubes 14, the respective ends of which are secured in or to the top and bottom rods 12 and 13 in any suitable manner.

The end filler tubes 15 and 16 inclose the guide rods 17 and 18, the lower ends of which

are positioned by the arrangement shown in Figs. 6 to 9 inclusive. In said figures it will be seen that I secure to the bottom of the crib post a small bracket 19, the securing being effected in any suitable manner such as rivets 20. The bracket 19 has at its lower end an outstanding horizontally extending lug 21 which is perforated as shown best in Fig. 8 to provide a comparatively narrow outer slot 22 with an inner circular enlargement 23 of sufficient diameter to admit the unreduced circular end of the guide rod 17. Adjacent to the lower end of said guide rod 17, I cut a rectangular notch 24 in the side of the rod thereby reducing its cross section sufficiently to enable the notched part of the rod to enter the comparatively narrow slot 22 in the lug 21.

One of the objects of the slot 22 is to permit a limited amount of movement of the lower end of the rod to or from the post thereby preventing the frame member 12 from cramping due to possible variations in the dimensions of various parts. The bottom end of the rod 17 is, nevertheless, normally prevented from moving into the enlargement 23 by reason of a small sheet metal stamping 25 perforated to fit loosely around the rod and having a pair of turned down spring lugs 26 to prevent said stamping from rotating on the lug 21 and also to hold the stamping itself against accidental upward movement away from said bracket.

It will be understood that the lugs 26 are formed with sufficient spring to snap over the bracket lug 21 so that said washer will be secured in so far as vertical movement is concerned.

The distance between the inner edge of the stamping 25 and the outer face of the vertical portion of the bracket 19 is such that the rod 17 is not permitted to enter the enlargement 23, but when it is desired to detach the guide rods 17 for shipping or any other purpose, the washer 25 is raised on the rod above the top edge of the vertical portion of said bracket 19 whereupon the rod can enter the enlargement 23 and may be removed. Preferably a soft rubber collar 28 is placed around the guide rod on the top of the plate 25 to act as a cushion or a noise preventer when the gate is lowered.

The top and bottom tubes 12 and 13 of the gate 11 are drilled out large enough to

freely accommodate the guide rods and preferably said drilled apertures 27 are slotted slightly as shown best in Fig. 4 in order to prevent outward spreading movement of the guide rods in operating crib lock. The actual locking of the crib side in its upper position is effected by means of a locking pin 28 which may be a rivet or other suitable part projecting from the ferrule 29 which closes the end of the upper tube 12.

Said pin or projection 28 cooperates with a slotted bracket 30 secured to the upper end of the post of the crib, said bracket comprising an intermediate part 31 by which it may be secured to the post in any desired manner and an upper lug 32 and lower lug 33. In the present instance the intermediate portion 31 of the bracket 30 is united to the post 10 by means of a screw 34 passing through the post and threaded into said part 31 and a pin 35 which prevents the bracket from twisting out of its position.

The upper lug 32 constitutes a pivotal bearing for a link controlling the transverse movement of the upper end of the guide rod 17, said link in the present instance comprising a bent portion 36 of the upper end of the rod, the extremity of said part 37 being bent down parallel with the rod to enter an aperture 38 drilled in the horizontal upper lug 32. The outer end of the lug 32 is extended as shown at 39 in order to form a stop which, as shown best in Fig. 3, limits the outward movement of the upper end of the guide rod. The inner side of the lug 32 is also provided with a bent-up ear 39^a which limits the inward movement of the guide rod. It will be observed that the stops 39 and 39^a are in effect symmetrically disposed with reference to the pivot so that the guide rod is the same distance from the post in either position.

The lower lug 33 of the bracket 30 is bent to form a right angle part with a depending extension 40, the lower end of which is shaped to form a sloping cam surface 41 so located as to be engaged by the pin when the crib side is raised vertically. The purpose of said cam surface 41 is to cause the locking pin to travel in a path behind the edge of the lug 33 when the crib side is raised. It will be manifest that during such cam controlled movement of the upper end of the crib the link 36 will swing into the dotted line position shown at 42 in Fig. 3. After the crib side has been raised sufficiently to enable the lower edge of the pin 28 to clear the upper edge of the horizontal portion of the lug 33, the top of the gate may be pulled outwardly, *i. e.*, toward the aperture so as to cause the locking pin 28 to drop through the opening or slot 43 into the locking slot 44 which is a continuation of the upper slot or opening 43.

It will be understood that the described details of construction are merely illustra-

tive of my invention, the scope of which should be determined by reference to the appended claims, said claims to be construed as broadly as possible consistent with the state of the art:

I claim:

1. The combination of a post provided with a substantially vertical guide, a gate having its lower end slidable on said guide and having an upper part capable of movement relative to said post, interengaging means respectively carried by said post and said upper part controlled by relative transverse movement of the post and said upper part and a link connecting said post and said upper part for controlling the said transverse movement.

2. In combination, a support, a frame member slidably arranged with reference to said support but capable of a limited amount of movement transversely of said support, interengaging means respectively carried by said support and frame member operable by said relative transverse movement of said support and frame member and a link pivotally mounted on said support and connecting said frame member to said support for limiting the said transverse movement.

3. In combination, a support, a frame member slidably arranged with reference to said support but capable of a limited amount of movement transversely of said support, interengaging means respectively carried by said support and frame member operable by said relative transverse movement of said support and frame member and a link pivotally mounted on said support and connecting said frame member to said support for limiting the said transverse movement, and stopping means for preventing outward swinging movement of said frame member.

4. In a crib the combination of a post, a guide rod having its lower end stationarily mounted with reference to said post and having its upper end movable transversely with reference to said post, a crib side slidable on said rod, and cooperating means respectively carried by said crib side and said post for locking said crib side to said post in an upper position, said means being disengaged upon relatively transverse movement of said crib side and said post, and a link connecting the upper end of said guide rod with said post to limit said transverse movement.

5. In a crib the combination of a post, a guide rod substantially parallel with said post and anchored thereto at its lower end, a crib side provided at its upper and lower ends with means slidably engaging said guide rod, a bracket secured to said post, a link connecting said bracket with the upper end of said guide rod and cooperating locking means respectively carried by said crib side and said bracket disengageable by a transverse inward movement of the crib

side subsequent to upward movement thereof, said link limiting said transverse movement.

6. In a crib the combination of a post, 5 a guide rod substantially parallel with said post and anchored thereto at its lower end, a crib side provided at its upper and lower ends with means slidably engaging said guide rod, a bracket secured to said post,

a link connecting said bracket with the upper end of said guide rod, and coöperating locking means respectively carried by said crib side and said bracket disengageable by a transverse inward movement of the crib side subsequent to upward movement thereof, 15 said link comprising an integral projection on the upper end of said guide rod.

MATTHEW F. BAYER.
